(57) **CLAIM**

(21) Appl. No.: **29/315,466**

The ornamental design for a 3 sided finger brush for oral hygiene, as shown and described.

(22) Filed: **Jun. 29, 2009**

DESCRIPTION

(51) **LOC (9) Cl.** 04-02

FIG. 1 is shown on a reduced scale and the broken line showing of a user's hand therein is for illustrative purpose only and forms no part of the claimed design. The broken lines showing a series of bumps illustrate portions of the finger brush that form no part of the claimed design.
